(57) **CLAIM**

The ornamental design for a steering wheel, as shown and described.

DESCRIPTION

Cross reference is made to copending U.S. design patent application serial no. 29/767,042 entitled “Display Screen with an Animated Graphical User Interface” by Wang et al., which was filed on even date herewith; U.S. design patent application serial no. 29/767,044 entitled “Display Screen with an Animated Graphical User Interface” by Wang et al., which was filed on even date herewith; U.S. design patent application serial no. 29/767,045 entitled “Display Screen with an Animated Graphical User Interface” by Wang et al., which was filed on even date herewith; U.S. design patent application serial no. 29/767,046 entitled “Display Screen with an Animated Graphical User Interface” by Wang et al., which was filed on even date herewith; and U.S. design patent application serial no. 29/767,047 entitled “Display Screen with an Animated Graphical User Interface” by Wang et al., which was filed on even date herewith.

FIG. 1 is a right side perspective view of a steering wheel showing our new design;

FIG. 2 is a front side perspective view of the steering wheel of FIG. 1;

FIG. 3 is a front side elevational view of the steering wheel of FIG. 1;

FIG. 4 is a rear side elevational view of the steering wheel of FIG. 1;

FIG. 5 is a right side elevational view of the steering wheel of FIG. 1;

FIG. 6 is a left side elevational view of the steering wheel of FIG. 1;

FIG. 7 is a top plan view of the steering wheel of FIG. 1; and, FIG. 8 is a bottom plan view of the steering wheel of FIG. 1.

The broken lines shown in the drawings illustrate portions of the steering wheel that form no part of the claimed design.

(Continued)

The dash-dot-dash boundary lines illustrate the boundary of the claimed design and form no part of the claimed design.
